Primary Examiner—B. J. Bullock*Assistant Examiner*—Robert M. Spear*Attorney, Agent, or Firm*—Pitts & Brittian, P.C.**[57]****CLAIM**

The ornamental design of a combined mail, newspaper and parcel delivery box, as shown and described.

DESCRIPTION

FIG. 1 is a perspective view of a combined mail, newspaper and parcel delivery box showing my new design;

FIG. 2 is a front elevation view thereof;

FIG. 3 is a right side elevation view thereof;

FIG. 4 is a left side elevation view thereof;

FIG. 5 is a rear elevation view thereof;

FIG. 6 is a top plan view thereof;

FIG. 7 is a bottom plan view thereof;

FIG. 8 is a perspective view of an alternate embodiment of a combined mail, newspaper and parcel delivery box showing my new design;

FIG. 9 is a front elevation view thereof;

FIG. 10 is a right side elevation view thereof;

FIG. 11 is a left side elevation view thereof;

FIG. 12 is a rear elevation view thereof;

FIG. 13 is a top plan view thereof; and,

FIG. 14 is a bottom plan view thereof.

The broken lines in FIGS. 1-5, 7-12 and 14 form no part of the ornamental design.
